UNITED STATES PATENT OFFICE.

EDWARD L. PITTS, OF RATON, NEW MEXICO, ASSIGNOR OF ONE-HALF TO WILLIAM A. ROHR, OF RATON, NEW MEXICO.

EGG CARTON.

Application filed March 1, 1924. Serial No. 696,265.

To all whom it may concern:

Be it known that I, EDWARD L. PITTS, a citizen of the United States, and a resident of Raton, in the county of Colfax and State 5 of New Mexico, have invented certain new and useful Improvements in Egg Cartons, of which the following is a specification.

My present invention relates generally to egg cartons and more particularly to one 10 intended for individual shipments of eggs through the mail, my object being the provision of a carton which may be readily and quickly set up and collapsed as well as one which will be simple and inexpensive 15 and may be formed in its entirety from a one-piece blank without the necessity of extra fastening means.

Referring now to the accompanying drawings which illustrate my present invention 20 and form a part of this specification,

Figure 1 is a perspective view illustrating my improved carton complete and set up ready for shipment,

Figure 2 is a transverse sectional view 25 taken substantially on line 2—2 of Figure 1,

Figure 3 is a plan view of the blank from which the carton of Figure 1 is formed,

Figure 4 is a section taken horizontally 30 through the carton, illustrating a slight modification,

Figure 5 is a vertical transverse section taken on line 5—5 of Figure 4,

Figure 6 is a vertical longitudinal section taken on line 6—6 of Figure 4, and

Figure 7 is a plan view of the blank from 35 which the carton of Figures 4 to 6 inclusive is formed.

Referring now to these figures my invention proposes a carton for eggs of the general rectangular form indicated at 10 in Figure 1, the carton being of flattened elongated shape adapted to support therein two parallel longitudinal series of eggs 11 as indicated in Figure 2 and having a bottom 12, top 13, front and rear sides 14 and 15, ends 16 and a cover 17, the latter formed integral with and being a continuation of the rear side wall 15 and arranged to cover the major portion of the front wall 14 by 45 means of its front flap 18 in the closed position, said front flap 18 being cut away to provide a central extension 19 from the sides of which lateral locking tongues 20 project. To receive these tongues the forward side 50 wall 14 has spaced slots 21.

The carton thus constituted is formed from a blank 22 shown in Figure 3 of which the forward portion is bent upwardly and inwardly along the lines 23 and 24 so as to form between these lines the front wall 14, that section of the forward portion of the blank between line 24 and the line 25 forming the top 13 of the carton and having a terminal flap 26 beyond the line 25 which is turned downwardly against the inner surface of the rear side wall 15 as seen in Figure 2, to which said flap may be secured if it is so desired.

The rear portion of the blank is then bent upwardly and forwardly along lines 27 and 28, that portion of the blank between lines 23 and 27 forming the bottom 12 of the carton and that portion thereof between lines 27 and 28 forming the rear side wall 15. The rear portion of the carton beyond line 28 forms the cover 17 and its flap 18, the latter being bent downwardly along the line 29.

The ends 16 are formed by lateral extensions 30 of the blank projecting from the opposite sides of that section thereof forming the top 13 and after the forward section of the blank has been bent upwardly and inwardly as previously described, the extensions 30 are bent downwardly along lines 31 coinciding with the side edges of the blank and are then bent inwardly along lines 32 so as to form extension flaps 33 on the ends 16 adapted to project into the carton upon the upper inner surface of the bottom 12 it being noted that these extensions 33 are provided with spaced openings 34 for a purpose which will be presently described.

That section of the blank which forms the top 13 of the carton is provided with a plurality of rectangular areas each of which areas has cross slits as at 35 and curved corner slits as at 36 so as to constitute the required number of egg receiving and holding apertures by simply pressing the eggs downwardly through the slotted portions of the top so that the tongues of material between the slits extend downwardly along the sides of the eggs as indicated at 37 in Figures 2, 5 and 6 and press against and yieldingly hold the eggs in upright position, the top 13 being spaced vertically from the base or bottom 12 a distance substantially less than the lengthwise dimension of an egg. In so

doing the lower pointed ends of the eggs at the ends of the carton enter the openings 34 of the end flaps 33 and thus lock the ends 16 in place with the cooperation of the cover 17 which holds the eggs downwardly against the bottom 12 at all times by virtue of its passage over the larger ends of the eggs and its before-described locking connection with the front wall 14.

10 It thus becomes obvious that the erection of the carton may be easily and quickly accomplished and upon removal of the eggs therefrom, the carton may be just as quickly unfolded or collapsed for return shipment in a flatwise folded state.

15 If found necessary, a lengthwise reinforcing web or wall 38 may be utilized centrally within the carton, with a lower flap 39 attached as seen in Figures 4 and 5 centrally along the upper inner surface of the base or bottom 12. In this form, as shown in Figures 4 to 7 inclusive the ends of the central reinforcing web or wall 38 which in its upright effective position extends between the base 12 and the top 13, is terminated at its ends in spaced relation to the ends of the carton and the turned-in end flaps 33^a with their egg receiving apertures 34^a are centrally slotted as at 40 so that they are thus adapted to straddle the ends of the reinforcing web or wall 38 and brace the latter in its upright position. Otherwise than the features just mentioned, that is the central lengthwise reinforcing web or wall 38 and the slotting of the end flaps, the form of the invention shown in Figures 4 to 7 inclusive is the same as that illustrated in Figures 1, 2 and 3 and may be plainly seen from a comparison of the folded cartons in Figures 2 and 5 and the blanks in Figures 3 and 7 although it is to be noted from a comparison of Figures 2 and 5 that instead of a forward end flap 26 bent downwardly along the inner surface of the rear wall 15, the top 13 may as seen in Figure 5 be provided with a terminal flap 41 along its free edge bent upwardly along the inner surface of the rear wall 15 between the top 13 and the cover 17.

20 50 I claim:

1. An egg carton having its body provided with top, bottom, side and end walls, and also having a cover forming a continua-

tion of the rear side wall thereof and provided with a terminal flap having an interlocking connection with the front wall of the body, the said top wall of the body having slotted portions forming egg receiving apertures and the said end walls being lateral continuations of the said top wall and having turned flaps overlying the end portions of the bottom and provided with spaced openings to receive therethrough portions of the eggs placed through the receiving apertures of the top whereby to lock the end walls and their flaps in place when the carton is filled with eggs.

2. An egg carton having its body provided with top, bottom, side and end walls, and also having a cover forming a continuation of the rear side wall thereof and provided with a terminal flap having an interlocking connection with the front wall of the body, the said top wall of the body having slotted portions forming egg receiving apertures and the said end walls being lateral continuations of the said top wall and having turned flaps overlying the end portions of the bottom, and a centrally disposed lengthwise reinforcing web foldably connected to the bottom and upstanding into engagement with the top, the said flaps of the end walls being slotted to straddle the ends of the said reinforcing web whereby to brace the latter in upright position.

3. An egg carton having its body provided with top, bottom, side and end walls and having a cover forming a continuation of one of the side walls and adapted to overlie the top wall in spaced relation thereto, said cover and the other side wall having relatively engaging locking means to hold the cover in place and said top wall having slotted portions forming egg receiving apertures and egg engaging tongues around the apertures, within which the eggs are held between the bottom wall and the said cover, the said end walls forming lateral continuations of the top wall of the body and having means extending within the carton and engageable by certain of the eggs therein when filled to lock the end walls against displacement.

EDWARD L. PITTS.
